(57) **CLAIM**

I claim the ornamental design for a handle, as shown and described.

DESCRIPTION

FIG. 1 is a perspective view of a handle of the present invention, with a brush head shown in broken lines; FIG. 2 is an end view thereof; FIG. 3 is a rear end view thereof; FIG. 4 is a top plan view thereof; FIG. 5 is a bottom plan view thereof; and, FIGS. 6 and 7 are opposite side elevational views thereof. The broken lines are for illustrative purposes only and form no part of the claimed design.
